DESIGN FOR A VENETIAN BLIND

Nathaniel B. Wales, Detroit, Mich.

Application February 1, 1943, Serial No. 109,408

Term of patent 14 years

To all whom it may concern:

Be it known that I, Nathaniel B. Wales, a citizen of the United States, residing at The Wardell, 15 East Kirby Avenue, Detroit, Wayne County, Michigan, have invented a new, original, and ornamental Design for Venetian Blind, of which the following is a specification, reference being had to the accompanying drawing, forming a part thereof, wherein:

Fig. 1 is an elevational view of a Venetian blind embodying my new design, in extended and closed position, taken from the inside thereof;

Fig. 2 is an enlarged, vertical section taken on the line 2—2 of Fig. 1; and,

Fig. 3 is a view similar to Fig. 2 but showing the blind in open position.

The dominant feature of the design consists in a representation of the sash of a window having a plurality of panes on the light reflecting inner face of a Venetian blind when in extended and closed position.

I claim:

The ornamental design for a Venetian blind, substantially as shown and described.

NATHANIEL B. WALES.
